UNITED STATES PATENT OFFICE.

NICHOLAS HOWARD WARNOCK, OF ASHFORD, ALABAMA.

BELT-TIGHTENER FOR SAWMILL FEED MECHANISMS.

No. 850,698.

Specification of Letters Patent.

Patented April 16, 1907.

Application filed November 8, 1906. Serial No. 342,537.

To all whom it may concern:

Be it known that I, NICHOLAS HOWARD WARNOCK, a citizen of the United States, residing at Ashford, in the county of Houston 5 and State of Alabama, have invented new and useful Improvements in Belt-Tighteners for Sawmill Feed Mechanism, of which the following is a specification.

This invention relates to belt-tighteners for sawmill feed mechanism in which the traverse of the log-carriage is effected by belts adapted to shift the carriage either to or from the saw, as the case may be; and the object thereof is to provide such mechanism 10 with a rocking frame carrying idler-pulleys which are adapted to alternately engage the belts to move them into driving engagement with a shifting mechanism for the carriage.

Further objects of the invention consist in 15 providing a sawmill feed mechanism which shall be simple in its construction, strong, durable, efficient in its use, conveniently operated, readily set up with relation to the carriage and saw, and comparatively inexpensive to manufacture.

With the foregoing and other objects in view the invention consists of the novel construction, combination, and arrangement of parts hereinafter more specifically described, 20 and illustrated in the accompanying drawings, wherein is shown the preferred embodiment of the invention; but it is to be understood that changes, variations, and modifications can be resorted to which come within 25 the scope of the claim hereunto appended.

In describing the invention in detail reference is had to the accompanying drawings, wherein like reference characters denote corresponding parts throughout the several 30 views, and in which—

Figure 1 is a top plan view of a sawmill feed mechanism in accordance with this invention. Fig. 2 is a sectional side elevation. Fig. 3 is a detail showing the rocking frame.

Referring to the drawings by reference characters, 1 denotes a base in which is journaled a saw-arbor 2, carrying a driven pulley 3 therefor, and 4 denotes a saw suitably secured to the arbor. Upon the saw-arbor 2 45 are the flanged pulleys 5 and 6, the latter being of greater diameter than the former. Journaled in the base 1 is a drive-shaft 7 for the log-carriage. (Not shown.) The shaft 7 carries a pinion 8, which engages with the 50 ordinary rack (not shown) of a log-carriage for driving the same.

The shaft 7 is adapted to be rotated in either direction; but when rotated to feed the carriage to the saw the speed of the shaft 7 is less than the speed thereof when it is rotated 60 to shaft the carriage from the saw. Fixed to the shaft 7 suitable distances apart is a pair of flanged pulleys 9 10. The former when operated is adapted to rotate the shaft 7 so as to shift the carriage toward the saw, and 65 the reverse action of the shaft 7 is had when the pulley 10 is operated. The pulleys 9 10 are of the same diameter; but the pulley 9 is of larger diameter than the pulley 5, the pulley 9 being driven from the pulley 5 in a 70 manner as hereinafter set forth. The pulley 10 is of larger diameter than the pulley 6 and is driven from said pulley in a manner as hereinafter set forth.

The reference character 11 denotes a belt 75 which is adapted to intermittently engage the pulley 9 and operate it, and in this connection it will be stated that the belt 11 travels over the pulley 5 and also over an idler-pulley 12, which is carried by a shaft 13, journaled in the base 1. The belt 11 is adapted to be engaged by a shiftable flanged belt-tightener pulley 14, so as to draw the belt taut and cause it to operatively engage with the pulley 9 so as to drive it. The manner in 80 which the idler-pulley 14 is shifted so as to pull the belt 11 taut will presently be explained. The pulley 10 is operated through the medium of a belt 15, which passes over the pulley 6 and also over the pulley 10; but 85 normally this belt loosely passes over the said pulleys. The belt 15 is drawn taut through the medium of a shiftable flanged belt-tightener pulley 16, so as to cause a driving of the pulley 10 from the pulley 6. 90 When the pulley 10 is driven, it will cause the rotation of the shaft 7 and shift the carriage from the saw. The shaft 7 when driven by the pulley 10 rotates at a greater rate of speed than when driven by the pulley 9. 95

The latter when operating the shaft shifts the carriage to the saw. The manner in which the idler-pulley 16 is shifted to draw the belt 15 taut will presently be referred to.

Loosely mounted upon the shaft 7 is a 105 rocking frame formed of three members 17, 18, and 19, the member 18 being the intermediate member and of approximately double the length of either of the members 17 and 19. The member 18, centrally thereof, is 110 provided with an opening, so that the same can be mounted upon the shaft 7, while the

rear end of the member 17 and the forward end of the member 19 are provided with openings in alignment with the opening in the center of the member 18, so that the three members of the frame can be loosely mounted upon the shaft 7. The forward ends of the member 17 and the member 18 are rigidly connected together by the holdfast device 20 in the form of a bolt and nut, and such bolt constitutes a shaft for the idler-pulley 16. Suitable collars 21 are provided upon the bolt, so as to prevent the lateral movement of the idler-pulley 16 upon the bolt. The rear ends of the members 18 and 19 are rigidly connected together by a holdfast device 22 in the form of a bolt and nut, and such bolt constitutes a shaft for the idler-pulley 14. Suitable spacing-collars 23 are provided upon the bolt to prevent the lateral movement of the idler-pulley 14.

The rocking frame is shifted through the medium of a pair of inclined links 24, which at their forward ends are attached to the members 17 and 18 by lag-screws 24^a and at their rear ends are connected, as at 25, to an operating-lever 26, pivoted at its lower end, as at 27, to the base 1.

If the lever 26 is shifted forwardly, it will lower the forward end of the frame so as to bring the idler-pulley 16 into engagement with the belt 15 and cause the belt to operatively engage the pulleys 6 and 10. Consequently the pulley 10 will be driven and cause the rotating of the shaft 7, which will shift the feed-carriage from the saw. After the carriage has been moved from the saw the desired extent then if the lever 26 be shifted rearwardly it will rock the frame so as to lower the rear end thereof and bring the idler 14 into engagement with the belt 11, consequently drawing the said belt 11 taut and cause it to operatively engage the pulley 9, thereby driving it and rotating the shaft 7 in a direction opposite to that in which it is rotated by the pulley 10 and cause the shifting of the carriage toward the saw.

It will be evident from the foregoing description, taken in connection with the accompanying drawings, that a sawmill feed mechanism is set up which is extremely sim-

ple in its construction and positive in its operation, and it is thought the advantages of such construction can be generally understood.

What I claim is—

A feed mechanism comprising a drive-shaft, a pair of pulleys mounted upon said shaft and one of which is of greater diameter than the other, a driven shaft, a pair of pulleys fixed upon said driven shaft, a rotatably-supported idler-pulley, a belt 11 loosely engaging the pulley of smaller diameter and the said idler and one of the pulleys upon said driven shaft, a belt 15 loosely engaging the said pulley of greater diameter and the other of the pulleys upon said driven shaft, a rocking arm pivoted intermediate its ends upon said driven shaft, a pair of arms pivoted at one end upon said driven shaft, extending in opposite directions with respect to each other and each of which is of less length than the rocking arm, connections between the free end of one of said short arms and one end of said rocking arm, an idler-pulley carried by said connections and adapted to be moved into engagement with the belt 11 and draw it taut when said rocking arm is shifted in one direction causing thereby the operation of one of the pulleys upon said driven shaft and the operation of said latter shaft, connections between the free end of the other of said short arms and the other end of said rocking arm, an idler-pulley mounted upon the last-mentioned connection and adapted when the rocking arm is shifted in the opposite direction to draw the belt 15 taut thereby causing the operation of the other of the pulleys upon the driven shaft, and the reversal of movement of said latter shaft, a pair of inclined links connected with one end of said rocking arm and with one end of one of the short arms, and a lever pivoted to said links for actuating them.

In testimony whereof I have hereunto set my hand in presence of two witnesses.

NICHOLAS HOWARD WARNOCK.
